UNITED STATES PATENT OFFICE.

WILLIAM MAILLER, OF ST. JOSEPH, MISSOURI.

FILTER.

SPECIFICATION forming part of Letters Patent No. 423,615, dated March 18, 1890.

Application filed August 5, 1889. Serial No. 319,711. (No model.)

To all whom it may concern:

Be it known that I, WILLIAM MAILLER, of St. Joseph, in the county of Buchanan and State of Missouri, have invented a new and 5 useful Improvement in Filters, of which the following is a full, clear, and exact description.

My invention relates to an improvement in filters, and has for its object to provide a filter of simple, durable, and economical construction, capable of effectually extracting the impurities from water, and also capable of being attached to a faucet of any description.

15 The invention consists in the novel construction and combination of the several parts, as will be hereinafter fully set forth, and pointed out in the claims.

Reference is to be had to the accompanying 20 drawings, forming a part of this specification, in which similar figures of reference indicate corresponding parts in all the views.

Figure 1 is a central vertical section through one of the filter-tubes. Fig. 2 is central vertical section through the complete filter. Fig. 25 3 is a partial vertical section taken at a right angle to the section shown in Fig. 2. Fig. 4 is a plan view of one of the filter-tubes, and Fig. 5 is a section on line $x-x$ of Fig. 2.

30 I will first describe in detail one of the filter-tubes, as all of the said tubes are identical in construction, which consists of a body 10, tubular and preferably round, of any desired length, and of any suitable material.

35 Near the bottom of the body, which is exteriorly threaded, as shown at 11 in Fig. 1, a preferably annular flange 12 is formed integral with the inner wall, upon which flange an

apertured or perforated metal disk 13 is placed, 40 which disk is of a diameter essentially equal to the inner diameter of the body and covered at the top, bottom, and sides with an asbestos cloth 14, which cloth is woven in such manner as to admit of the passage of water

45 through the same under pressure. The interior of the body 10, above the bottom sieve or screen formed by the disk and its covering, is partially filled with a clear sand 15, as illustrated in Fig. 1. Upon the top of the

50 sand, which is packed down by hand as closely as possible, an apertured or perforated disk 16 is placed, which disk is also covered

with asbestos cloth, and upon the inner face of the covered disk 16 an apertured or perforated cork disk 17 is placed, this latter disk 55 being made to tightly fit the interior wall of the body, the purpose of the cork disk being to prevent any water passing up in contact with the sides of the body, which is liable to happen if covered metal disks only are employed. 60 Above the cork disk two more disks 18 and 19 are placed, constructed in similar manner to the disk 16, and upon the upper disk 19 an uncovered metal perforated or apertured disk 20 is placed. The end of the body in which the 65 series of disks is located is provided upon opposite sides with a lug 21, and the angular extremities of a bail 22 are made to contact with the said lugs, as shown in Fig. 1, which bail is provided at the center of its bow-section with a threaded aperture, adapted to receive a screw 23, the lower end of which screw contacts with the upper metal disk 20.

It will thus be observed that by manipulating the screw 23 sufficient pressure will be 75 exerted upon the series of disks below the screw to closely pack the sand in the body. After the damp or wet sand has been compressed as much as possible the upper disks are released from the pressure of the screw 80 and removed from the body and a fresh supply of dry sand is introduced in sufficient quantity to fill the space gained by the last compression. The disks are now placed in position again within the body, the bail 85 brought in contact therewith, and the screw made to bind firmly upon the upper disk and manipulated to further compress the body of sand.

Upon the exteriorly-threaded end of the 90 body 10 a cap 24 is screwed, from which cap a tube 25 is projected, preferably from a central point.

A number of tubes constructed as above described are placed within a suitable jacket 95 26, as shown in Figs. 2, 3, and 5, which jacket is provided with a cap 27 at one end, and immediately beneath the cap a water-supply pipe 28 is projected transversely within the jacket, and the several tubes 25, radiating 100 from the caps of the filtering-tubes, are connected with this supply-pipe, as shown in Figs. 2 and 5.

Having thus described my invention, I

claim as new and desire to secure by Letters Patent—

1. In a filter, the combination, with a tubular body having a screen or sieve firmly secured near one end, and a body of sand placed upon the said screen or sieve, of a series of screens or sieves and an interposed apertured corked disk placed in the opposite end of the body, a bail attached to the body, and a screw carried by said bail, capable of contact with the outer disk to exert pressure thereon, substantially as shown and described.
2. In a filter, the combination, with a series of tubular bodies having a screen or sieve firmly secured to one end, a body of sand placed upon the said screen or sieve, a series of screen or sieves and an interposed cork disk placed in the opposite end of the body, a bail attached to the body, and a screw carried by said bail, capable of contact with the outer disk to exert pressure thereon, of a jacket open at one end and capped at the other surrounding the said series of tubes, a water-supply pipe projected within the capped end of the jacket, a cap covering one end of each tube, and branch pipes connecting each tube-cap with the supply-pipe, substantially as shown and described.
3. In a filter, the combination, with a tubular body having a screen or sieve held diametrically therein near one end, and provided with a packing or filling of sand which is supported by said disk, of a series of screens or sieves placed in the opposite end

of the body above the sand, each consisting of a metal apertured or perforated disk and a covering of asbestos cloth, and a cork disk closely fitting the interior of the body, introduced between the said series of disks, and means, substantially as shown and described, for exerting a continual pressure upon the outer disk of the series, substantially as and for the purpose specified.

4. In a filter, the combination, with a tubular body provided with a cap attached to one end, a screen diametrically supported within the body a distance from the capped end, said screen consisting of an apertured metal disk having a covering of asbestos cloth, and a sand filling closely packed within the tube upon the said screen, of a series of screens introduced in the opposite end, bearing upon the sand filling, said screens comprising perforated or apertured disks covered with asbestos cloth, a perforated or apertured cork disk located between the covered metal disks, the cork disk closely fitting the inner walls of the body, and an upper or outer uncovered metal perforated disk, a bail held in contact with the uncapped end of the disk, and a screw carried by said bail contacting with the uncovered metal disk to exert pressure thereon, all combined for operation substantially as shown and described.
